UNITED STATES PATENT OFFICE.

MECKLEY MASTERSON, OF CHICAGO, ILLINOIS.

VIOLIN BASS-BAR.

1,333,088.

Specification of Letters Patent.

Patented Mar. 9, 1920.

Application filed June 30, 1919. Serial No. 307,690.

To all whom it may concern:

Be it known that I, MECKLEY MASTERSON, a citizen of the United States, and a resident of the city of Chicago, county of Cook, and State of Illinois, have invented certain new and useful Improvements in Violin Bass-Bars, of which the following is a specification.

My invention relates to improvements in bass bars for violins and has for its object the provision of a bass bar which is adapted to improve the tone of the instrument with which used.

Other objects will appear hereinafter.

The invention consists in the combination and arrangements of parts hereinafter described and claimed.

The invention will be best understood by reference to the accompanying drawings forming a part of this specification, and in which,

Figure 1, is a top plan view of a violin embodying my invention.

Fig. 2, is a top plan view of my invention.

Fig. 3, is a side elevational view of the invention applied to a violin.

Fig. 4, is a transverse sectional view of the invention taken on substantially line 4—4 of Fig. 3.

The invention is designed primarily to be used on a violin or a musical instrument of this class. The invention is adapted to be secured to the under surface of the front plate or belly of the violin body. The device consists of an elongated bass bar 8, this bass bar being of the usual type of bass bars used with string instruments of this class. Projecting laterally from the member 8 intermediate the ends thereof, and preferably made integral therewith is a comparatively thin member 9. As shown in Fig. 4, the upper face of the member 9 lies in a plane which is beneath the plane in which the upper face of the member 8 lies. Projecting from the free end of the member 9 and extending parallel to the member 8 is a sound-post-engaging member, 10. The upper face of the member 10 is positioned above the upper face of the member 9 so as to lie in the same horizontal plane with the upper face of the member 8. In applying the device to a violin or a similar string instrument with which it is adapted to be used, the upper face of the member 8 and the upper face of the member 10 is

glued or otherwise fastened as at 6 and 6'. Projecting downwardly from the member 9 is a stud or post 11 the upper end of which is securely fastened to member 9. Mounted to the lower end of the post 11 is a hollow box-like member 12 closed on all sides except at the under side wherein is provided an opening 13. Mounted upon the under side of the box-like member 12 adjacent the opening 13 is a flaring member 14.

The entire device is designed to be constructed of wood or some other fibrous material and the walls of the box 12 are designed to be made of very thin material to afford a device which will be adapted to vibrate easily. The box 12 acts as a resonator in the musical instrument, when same is played, and serves the purpose of augmenting the tone of the musical instrument and producing a finer and fuller tone than is now customarily produced in such instances.

Another purpose which my invention accomplishes is to afford a uniformly level object upon which the upper end of the sound-post 7 may engage. The member 10 is adapted to engage the upper end of the sound-post 7. Owing to the bow shape of the front plate or belly of the violin, the upper end of the sound-post 7 ordinarily engages the under surface of the front plate or belly of the violin at only one point. To regulate the tone of the violin, it is necessary that the position of the post 7 relatively to the ends of the violin be changed. By engaging the upper end of the sound post 7 with the uniformly horizontal under-surface of the member 10 a more secure and efficient contact is thereby formed.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. The combination with a bass bar having a laterally projecting member, of a resonator depending from said projecting member, substantially as described.

2. The combination with a bass bar having a laterally projecting member, of a resonator depending from said projecting member and spaced therefrom, substantially as described.
3. A device of the class described comprising a bass bar; a laterally projecting member secured to said bass bar; resonating means depending from said member and spaced therefrom, substantially as described.
4. A device of the class described comprising a bass bar; a laterally projecting member secured to said bass bar adjacent one edge thereof; and resonating means depending from said member, substantially as described.
5. A device of the class described comprising a bass bar; a laterally projecting mem-

ber secured to said bass bar adjacent one edge thereof; and resonating means depending from said member and spaced therefrom, substantially as described.

6. A device of the class described comprising a bass bar; a laterally projecting member secured to said bass bar adjacent one edge thereof; a post projecting downwardly from said member; and resonating means secured to the lower end of said post, substantially as described.

In testimony whereof I have signed my name to this specification in the presence of two subscribing witnesses.

MECKLEY MASTERSON.
